UNITED STATES PATENT OFFICE

157,914

CARD HOLDING DEVICE

Sidney P. Shipman, Rockville Centre, N. Y.

Application June 25, 1949, Serial No. 3,555

Term of patent 7 years

(Cl. D74—1)

To all whom it may concern:

Be it known that I, Sidney P. Shipman, a citizen of the United States of America, residing in Rockville Centre, county of Nassau, and State of New York, have invented a new, original, and ornamental Design for a Card Holding Device, of which the following is a specification, reference being had to the accompanying drawing, forming part thereof, wherein,

I claim:

The ornamental design for a card holding device, substantially as shown.

SIDNEY P. SHIPMAN.
